J. J. & T. E. FEARON.
DEVICE FOR REGULATING DELIVERY OF PLASTIC SUBSTANCES.
APPLICATION FILED APR. 8, 1909.

960,081.

Patented May 31, 1910.

UNITED STATES PATENT OFFICE.

JAMES J. FEARON AND THOMAS E. FEARON, OF PHILADELPHIA, PENNSYLVANIA,
ASSIGNORS, BY MESNE ASSIGNMENTS, TO THE BANDING MACHINE COMPANY, OF
WILMINGTON, DELAWARE, A CORPORATION OF DELAWARE.

DEVICE FOR REGULATING DELIVERY OF PLASTIC SUBSTANCES.

960,081.

Specification of Letters Patent.

Patented May 31, 1910.

Application filed April 8, 1909. Serial No. 488,784.

To all whom it may concern:

Be it known that we, JAMES J. FEARON and THOMAS E. FEARON, both citizens of the United States, residing in Philadelphia, Pennsylvania, have invented certain Improvements in Devices for Regulating Delivery of Plastic Substances, of which the following is a specification.

Our invention relates to devices employed for delivering either continuously or intermittently limited and regulated quantities of plastic material, such as paste or other adhesive substance, lubricating greases, cake batter, dough, or the like, the object of our invention being to so construct such a device as to positively and accurately regulate the amount of delivery, to prevent leakage between successive deliveries, and to maintain the material in a moist or soft condition for relatively long periods of time when no deliveries are being made. This object we attain in the manner hereinafter set forth, reference being had to the accompanying drawing, in which—

Figure 1 is a view, partly in elevation and partly in vertical section, of a device constructed in accordance with our invention, for delivering plastic material; Fig. 2 is a front view of part of the device with the delivery nozzle in section; and Fig. 3 is a plan or top view of the device.

In Fig. 1 of the drawing, 1 represents the main receptacle for the plastic material, which for convenience we will term "paste," this receptacle, in the present instance, being inclined at its lower end so as to form a projecting inclined spout 2, which terminates in a nozzle 3 of contracted diameter, having a delivery opening α in the bottom of the same.

Fitting snugly to the main portion of the receptacle 1 is a plunger 4 with leather washer 4^a, said plunger being normally depressed by means of a coiled spring 5 surrounding the stem 6 of the plunger and contained within a cap 7 applied to the upper end of the receptacle 1, the outer end of this cap having a tubular screw plug 9 which bears upon the upper end of the spring 5, whereby adjustment of the plug in respect to the cap determines the tension of the spring.

The plunger stem 6 passes through the tubular plug 9 and is threaded at its upper

end for the reception of a nut 10. As the 55 spring 5 expands its power correspondingly decreases, and, in order to prevent the expansion of the spring to such an extent that the plunger will not apply sufficient force to the paste in the receptacle 1, the forward 60 movement of the plunger is arrested at intervals by contact of the nut 10 with the top of the plug 9, readjustment of the plug being then effected in order to increase the tension of the spring. 65

The axis of the delivery nozzle 3 is parallel with that of the receptacle 1, the axis of the delivery mouth of the nozzle is parallel with that of the nozzle itself and the nozzle is connected to the receptacle by means of an 70 inclined neck so that there is but little, if any, obstruction to the flow of the material from the receptacle to the nozzle, consequently the pressure upon the material in the nozzle is not affected by any sharp 75 changes in the direction of flow of the material from the receptacle to the outlet.

As the plunger 4 exerts a constant pressure upon the mass of paste in the receptacle 1, means are employed to regulate the volume of the stream delivered from the nozzle, when the same is continuous, or prevent the ejection of the paste from the nozzle in a continuous stream when an intermittent discharge is desired. These objects are attained by providing the nozzle 3 with a feed screw 11 of relatively coarse pitch and fitting snugly to the interior of the nozzle, said feed screw being secured to or forming part of a stem 12 which passes through a bushing 90 13 in the top of the spout 2 and carries at its upper end a bevel wheel 14 whose hub is rotatably mounted in a bearing, block 15 which rests upon said spout, embraces the receptacle and is split and provided with a 95 clamping screw 16, as shown in Fig. 3, so as to secure it firmly in position upon the receptacle.

The bevel wheel 14 meshes with a similar bevel wheel 17 upon a shaft 19, which is 100 adapted to suitable bearings on the block 15. If a continuous discharge of the paste is desired any suitable means may be employed for rotating this shaft 19 at a predetermined speed, but, in the present instance, an 105 intermittent discharge is provided for, the shaft 19 being equipped at its outer end with a ratchet wheel 20 engaged by a swing-

ing pawl 21 pivotally mounted upon an arm 22 which is free to swing upon the shaft 19.

The feed screw 11 offers sufficient frictional resistance to prevent any direct flow 5 of the paste through the nozzle 3 under the pressure to which said paste is subjected by the plunger 4, consequently, if the feed screw is continuously rotated, there will be continuous delivery of the paste from the 10 nozzle 3, in quantity determined by the speed of rotation of the feed screw, or, if the feed screw is intermittently actuated, there will be corresponding intermittent deliveries of paste from the nozzle, the volume 15 of each delivery being dependent upon the extent of partial rotary movement of the feed screw and the periods of delivery being timed to accord with the periods of movement of the feed screw, hence the latter can 20 be readily governed by the intermittent movements of the arm 22 and the volume of each delivery can be governed by the extent of each of such movements.

We find it advisable to bevel the opening 25 α of the nozzle 3 so that it flares outwardly, as shown in Fig. 2, an opening of this form providing for the delivery of the paste in a straight line and without any tendency to curl. It is also advisable to terminate the 30 feed screw 11 some distance short of the bottom of the nozzle, in order that a body of paste may intervene between the bottom of the feed screw and the outlet opening α , as this construction insures greater certainty in 35 the delivery of the material than is possible when the feed screw contacts with the bottom of the nozzle.

The receptacle being practically air-tight, there will be no drying or hardening of the 40 material contained therein, even if the delivery mechanism is not operated for a comparatively long time, the only portion of the material exposed to the air being at the delivery opening α , and if this exposed portion 45 becomes dry or hard the removal of a very small portion of the material at the outlet will be sufficient to render the device again operative.

When the material is plastic, the pressure 50 of the plunger thereon is sufficient to feed a constant supply of said material to the feed screw, but not sufficient to overcome the frictional resistance of said feed screw, and thus cause delivery of the material from the nozzle, consequently such delivery will be dependent upon the movement of the feed screw alone, and can thereby be accurately regulated or rendered intermittent as desired. In this respect our invention differs essentially from devices in which the plunger is actuated either continuously or intermittently by means of a feed screw, for, in such devices, accurate delivery, or delivery of small quantities at a time is practically impossible, since the delivery begins as soon

as the pressure upon the mass overcomes the frictional resistance to its movement, and continues until the frictional resistance again predominates, and a barely perceptible movement of the relatively large plunger will cause delivery of an excessive amount of material at the contracted nozzle. Both of these objections are overcome by locating the regulating device at the nozzle.

We claim:—

1. In a device of the character described, the combination of a receptacle having a contracted delivery nozzle whose axis is parallel with that of the receptacle, an inclined neck connecting the delivery nozzle 80 and receptacle, means for maintaining the material under pressure in the nozzle, and a rotatable feed regulating device located in said nozzle.

2. In a device of the character described, 85 the combination of a receptacle having a contracted delivery nozzle, whose axis is parallel with that of the receptacle, said nozzle having an outlet whose axis is coincident with that of the nozzle, an inclined 90 neck connecting the nozzle and the receptacle, means for maintaining the material under pressure in the nozzle, and a rotatable feed regulating device located in the nozzle.

3. In a device of the character described, 95 a receptacle having an inclosed delivery nozzle, means for maintaining the material under pressure in said nozzle, and means contained in said nozzle for regulating delivery therefrom, said means having, as an element, a spiral flange which prevents direct flow through the nozzle.

4. In a device of the character described, a receptacle having an inclosed delivery nozzle, means for maintaining the material under pressure in said nozzle, and a feed screw 105 contained in said nozzle and serving to regulate the delivery therefrom, said feed screw preventing direct flow through the nozzle.

5. In a device of the character described, 110 the combination of a receptacle having an inclosed delivery nozzle, means for maintaining the material under pressure in said nozzle, and movable delivery means in said nozzle which prevents direct flow there- 115 through, and, when quiescent, presents such frictional resistance to the flow of the material under pressure as to prevent delivery of the same.

6. In a device of the character described, 120 a receptacle having an inclosed delivery nozzle, means for maintaining the material under pressure in said nozzle, a feed screw combined with said nozzle, and preventing direct flow through the same, and means for 125 operating said feed screw.

7. In a device of the character described, a receptacle having an inclosed delivery nozzle, means for maintaining the material under pressure in said nozzle, a feed screw

combined with said nozzle, and preventing direct flow therethrough, and means for intermittently operating said feed screw.

8. In a device of the character described, 5 a receptacle having an inclosed delivery nozzle, means for maintaining the material under pressure in said nozzle, and a feed screw contained in said nozzle and preventing direct flow therethrough, said feed screw 10 terminating short of the delivery end of the nozzle.

9. In a device of the character described, 15 the combination of a receptacle having an offset or delivery spout with delivery nozzle thereon, having its axis parallel with that of the receptacle, means for maintaining the material under pressure in said nozzle, and a feed screw for governing the delivery from said nozzle, the stem of said feed screw 20 passing through the top of the deflected spout.

10. In a device of the character described, 25 the combination of a receptacle having a delivery nozzle, means for governing the delivery from said nozzle, mechanism for operating said delivery means, and a block detachably mounted upon the receptacle and carrying said operating mechanism.

11. In a device of the character described, 30 the combination of a receptacle having a delivery nozzle whose axis is parallel with that of the receptacle, means contained in said nozzle for governing the delivery therefrom, a transverse shaft disposed at a right angle to the axis of the nozzle, gearing connecting said shaft with the delivery means, and means for imparting intermittent movements of partial rotation to said shaft. 35

12. In a device of the character described, 40 the combination of a receptacle having an inclosed delivery nozzle, with outwardly flaring delivery opening, means for maintaining the material under pressure in said nozzle, and means contained in said nozzle for regulating delivery therefrom, said 45 means having, as an element, a spiral flange which prevents direct flow through the nozzle.

In testimony whereof, we have signed our names to this specification, in the presence 50 of two subscribing witnesses.
